(57) **CLAIM**

The ornamental design for a solar water heater, as shown and described.

DESCRIPTION

FIG. 1 is a top perspective view of a solar water heater;
FIG. 2 is a plan view of the invention illustrated in FIG. 1;
FIG. 3 is a side elevation view of the invention illustrated in FIG. 1;

FIG. 4 is an opposite side elevation view of the invention as compared to FIG. 3;

FIG. 5 is an end elevation view of the invention illustrated in FIG. 1;

FIG. 6 is an opposite end elevation view of the invention as compared to FIG. 5; and,

FIG. 7 is a bottom perspective view of the invention illustrated in FIG. 1.
